UNITED STATES PATENT OFFICE.

JAMES J. MURPHY, OF NEW HAVEN, CONNECTICUT.

AUTOMATIC VALVE AND THE LIKE.

Application filed February 8, 1927. Serial No. 166,853.

The present invention relates to automatically operating valves designed for use especially with radiators of steam heating systems. One object of the invention amongst others, is to produce an efficient valve which is comparatively simple in construction and positive in action. The various parts of the valve are constructed and arranged so as to permit of easy assembling and which parts are adjusted at the factory so that the valves may be set up for constant use without further adjustment.

The improved valve belongs to a class of valves which operate to permit expulsion of air from the system through the radiators under action of internal pressure generated by the expanding vapors. Furthermore, the valves are arranged to close automatically to prevent re-admission of air whereby a partial vacuum of low pressure is constantly maintained throughout the system thereby deriving the best working condition.

In carrying out the invention, the improved valve essentially comprises a casing enclosing a pair of diaphragms or flexing members and to distinguish one from the other, said flexing members will hereinafter be called upper and lower flexing members. The upper member is rigidly supported by the casing and the lower member is carried by a floating or movable member, in which internal expansion and contraction is created and operating so as to respectively effect the downwardly and upwardly flexing movement of the lower flexing member due to rise and fall in temperature. The improved valve also includes a siphon for draining any water which may accumulate within the valve due to condensation or other reasons. The upper flexing member carries an air-check valve body and said floating member carries the valve member, which latter is preferably in the form of a needle valve. A low pressure internal working condition of the valve is maintained in the chamber below the upper flexing member. This latter member is held on its support between a pair of rigid plates, one plate being adjustable whereby the degree of flexing movement of said upper flexing member may be determinately set or calibrated.

The improved valve having an embodiment of the invention adapted to a steam radiator of a heating system will be described hereinafter with reference to the accompanying drawings wherein:—

Figure 1 is a perspective view showing the improved valve attached to a radiator of which only a part is shown; and

Figure 2 is a longitudinal section showing the complete valve.

Referring to said drawings, the improved valve is constructed preferably of a drawn tubular shell or casing 1 having an open upper end covered by a cap 2. A threaded nipple 3 projects from the casing and by means of this nipple the valve is operatively connected with the radiator 4 in the usual manner. The casing has the flange 5 at the open upper end and this flange is externally threaded at 6 by means of which the upper flanged plate 7 is adjustably secured. Said flange 5 also provides a seat for the lower plate 8, which together with the upper flexing member or diaphragm 9 is fixedly secured to the casing by soldering, for example, so as to provide a hermetical seal. Said diaphragm 9 carries the body 10 of an air-check valve and this body moves with said diaphragm. Said body has a central bore 11 providing a vent and a tapered seat for the valve member 12. The latter member is carried by the floating hollow member 13 having a flexible bottom 14 constituting the lower flexing member of the valve. This member 14 rests on an upwardly raised bottom 15 of the valve casing 1. The air-check valve body 10 has seated thereon a check-plate 16 and this plate is square or shaped so as to fit within and turn with the dome 17 of the cap 2. This cap 2 has the lower edge 18 crimped under the flange 5 in a manner so that said cap cannot be removed. The cap is free to turn on its support and the object of turning this cap is to transmit turning movement to the air-check plate 16 whereby the seat for the check-plate 16 may be kept clean by periodic turning of the same and thereby ensure proper operation of this check-plate in the action of opening or closing the vent 11.

The improved valve is provided with the usual siphon to drain the water which may accumulate within the valve chamber and this siphon consists of a bent piece of tubing 19 which is passed through the nipple 3. This nipple has the usual flanged head 20 which is preferably braised on the casing. The end of the siphon tube 19 has a flange 21 which in assembling is passed through the elongated hole 22 in the casing. When the nipple is fixed in place, the siphon tube 19

cannot be removed and the opening 22 is not ever closed so as to prevent admission of the heated vapor or air which must pass into or through the valve.

- 5 In the operation of the improved valve, as previously pointed out, it is first desirable that an internal low pressure or partial vacuum should be maintained throughout the heating system. In the normal position of
10 the parts of the valve, when there is no heat, the lower flexing member is in its upwardly flexed position; the needle valve member 12 is open and the check-plate 16 is in position to close the vent 11. When heated steam enters the valve chamber, the rise of pressure will expel the air through the vent 11, the pressure being great enough to raise check-plate 16 against atmospheric pressure. As
15 the vapor becomes further heated a volatile substance within the floating member 13 will expand and create pressure so as to cause downward flexing of the lower flexing member 14, thereby raising the needle-valve 12 to engage its seat and thus close the vent 11.
20 25 The air forced out of the valve passes through the vent 23 in the cap 2 and this vent 23 is constantly open to the atmosphere. When the pressure within the chamber of the valve below the upper flexing member
30 35 9 falls below atmospheric pressure, the said member is flexed downwardly due to the atmospheric pressure admitted through hole 24 in plate 7. By this arrangement, a partial vacuum or low pressure condition is maintained within the valve and throughout the heating system.

Various modifications may be made without departing from the spirit of this invention and it is to be understood that any modification coming fairly within the appended claims shall be covered thereby.

I claim—

- 40 45 50 55 1. In a valve of the class described; a casing; upper and lower flexing members located within said casing, said flexing members operating to maintain an internal low pressure working condition within the valve chamber beneath the upper flexing member, the latter member hermetically sealing said chamber; an air check valve body having a vent leading from said chamber and being carried by said upper flexing member, a valve element for opening and closing said vent associated with and operated by said lower flexing member, said upper flexing member being flexed outwardly and inwardly respectively by internal pressure and ex-

ternal atmospheric pressure to act separately or conjunctively with the lower flexing member in the action of opening and closing said vent and said upper flexing member being supported between upper and lower plates; the lower plate being fixed on said casing and the upper plate being adjustably mounted on said casing whereby adjustment is effected to determinately limit the flexing movement of said upper flexing member.

2. In a valve of the class described the structure thereof comprising a tubular casing having a flanged open end, a cap for closing said open end, a floating member within said casing having a flexing diaphragm at the bottom thereof, a raised bottom of said casing supporting said floating member, a flexing upper diaphragm and a supporting plate therefor fixed within said casing and hermetically sealing the chamber below said upper diaphragm, an upper plate adjustably mounted on said flanged end of the casing and arranged to be adjusted to determinably limit the flexing movement of said upper diaphragm, an air-check valve body carried by said upper diaphragm, said check valve body having a vent therein, and a valve element carried by said floating member for opening and closing said vent.

3. In a valve of the class described the structure thereof comprising a tubular casing having a flanged open end, a cap rotatably mounted on said flange for closing said open end, a floating member within said casing having a flexing diaphragm at the bottom thereof, a raised bottom of said casing supporting said floating member, a flexing upper diaphragm and a supporting plate therefor fixed within said casing and hermetically sealing the chamber below said upper diaphragm, an upper plate adjustably mounted on said flanged end of the casing and arranged to be adjusted to determinately limit the flexing movement of said upper diaphragm, an air-check valve body carried by said upper diaphragm, said air check valve body having a vent therein and a valve element carried by said floating member for opening and closing said vent; a check plate closing said vent against admission of air therethrough and said plate being arranged to rotate with said cap.

Signed at New Haven, county of New Haven, State of Connecticut, this fourth day of February, 1927.

JAMES J. MURPHY.
